(57) **CLAIM**

The ornamental design for a tree mounted game hoist, as shown and described.

DESCRIPTION

FIG. 1 is a front elevation view of the tree mounted game hoist showing the new design

FIG. 2 is a right elevation view thereof;

FIG. 3 is a left elevation view thereof;

FIG. 4 is a top plan view thereof;

FIG. 5 is a bottom plan view thereof; and,

FIG. 6 is an isometric view thereof.

The broken line showing of environment in the drawings is included for the purpose of illustrating only and forms no part of the claimed design.

The ornamental design for a tree mounted game hoist as shown and described herein to aid hunters in field dressing harvested game.

A tree mounted hand operated hoist for field dressing game animals in remote areas, including a chain for connection to a tree.
